James Bennett of Vigo Indiana
Letters Patent

The schedule refers to in these letters Patent and making part of them containing a description with ands of the said James Bennett himself of his improvement in propelling mills on the force of the current or tide by a suspended water wheel and block.

To all to whom these presents shall come: Be it known that I James Bennett of the County of Vigo and State of Indiana have invented a new and useful improvement in propelling mills on horses by force of the current or tide by a suspended water wheel and head block, and that the following is a full and exact description of the construction and operation of the said machine as invented or improved by me.

The water wheel shaft may be 40 or 50 feet long, and to be horizontally across the stream. The head blocks are to slide between two posts at each end, which have ways for it to slide in, so that it may be raised or lowered as the water may require.

There are two large chains fastened to each head block and which go up around or over the pulleys on the top of the frame which is made in and which have large weights at the end of them heavy enough to balance the water wheel and head blocks, so as to make the wheel stand whenever it is set.

On the end of the water wheel shaft there is a wheel with 110 or 80 cogs in it which works in a wallow or 18 or 20 rounds, which is on a shaft that stands on the head blocks, which works up and down with the water wheel, and in this a upright shaft above the wallow there is a spur wheel with 50 or 60 cogs in it which is to work into a stationary shaft which is fitted from the bottom up as high as the water wheel ever wants to be raised, and on the top of the long upright shaft there is a spur wheel as large as it will bear not to knock the chain or head block.

The water wheel may be from 16 to 20 feet high and should have

Aug 10, 1832

6 or 8 Buckets and may be let into the water 3 or 6 feet deep & will work very well in a current that moves at the rate of two miles an hour. The water wheel is to be lowered out of the water to stop the mill by a lever which works in a roller having a hollow at each end, which roller is fastened on the stone head blocky walls the pulley shaft and moves two small pieces of timber fastened in the head blocks beside the chain and which go up to the hollowes that are on the roller shafts and have coggs so as to work without and by this lever the wheel is to be raised first acting in stopping the mill and according to the different stages of the water. To work this suspended water wheel in tide water which babbz and flour have two cog wheels on the stationary shaft so far apart as to let a wallow be thrown out of one into the other and the mill will continue the same way.

The head blocks are made by two side pieces having double notches in each end, about one foot from the end for the upper part lower head blocks to go through, and the end of the timbers to go through far enough to work on a groove further to slide in.
